UNITED STATES PATENT OFFICE.

JOHN A. MULLIGAN, OF NARRAGANSETT PIER, RHODE ISLAND.

ENVELOP-OPENER.

1,353,413.

Specification of Letters Patent. Patented Sept. 21, 1920.

Application filed December 26, 1918. Serial No. 268,261.

To all whom it may concern:

Be it known that I, JOHN A. MULLIGAN, a citizen of the United States, residing at Narragansett Pier, in the county of Washington, State of Rhode Island, have invented 5 certain new and useful Improvements in Envelop-Openers; and I do hereby declare the following to be a full, clear, and exact description of the invention, such as will 10 enable others skilled in the art to which it appertains to make and use the same.

The invention relates to an envelop opener, and has for its primary object to provide an 15 opener of this character wherein different sizes of envelops can be introduced and the ends thereof cut, the waste from the envelops being trapped so as to avoid the scattering thereof in the use of the opener, the 20 opener being of novel form to permit its easy operation and the cutting of envelops with dispatch.

Another object of the invention is the provision of an envelop opener of this character which is comparatively simple in construction, 25 thoroughly reliable and efficient in its operation, and inexpensive to manufacture.

With these and other objects in view the invention consists in the features of construction, combination and arrangement of parts 30 as will be hereinafter fully described, illustrated in the accompanying drawing, and pointed out in the claims hereunto appended.

In the drawing:—

Figure 1, is a vertical section through the 35 casing of the apparatus, from front to rear, the knives and their operating mechanism being in elevation.

Fig. 2, is a vertical section at right angles 40 to the section of Fig. 1, in the plane including the knife operating plunger, the knives and their operating mechanisms being again in elevation.

Fig. 3, is a detail sectional view on line 45 3—3 of Fig. 2 to show the bevel of a knife and the manner in which it engages and moves the stop rearwardly to uncover the wide slot and permit the cutoff end of the envelop to fall into the drawer beneath, the 50 drawer being shown in Figs. 1 and 2.

Fig. 4 is a horizontal section on the line 55 4—4 of Fig. 2 with the stop block advanced and the knives raised and showing how the stop block partly covers the slots through which the cutoff envelop ends drop.

Fig. 5, is a transverse section on line 5—5

of Fig. 2 and showing the pivotal mounting of the lower ends of the knives.

Fig. 6, is a section on line 6—6 of Fig. 2 and illustrating the mounting of the plunger and the connection of the knife operating links therewith.

Referring to the drawings, the envelop 65 opener comprises a casing 10, preferably of metal and provided near its bottom and spaced therefrom, with a transverse partition 11 forming a cutting bed. In this bed, 70 are formed the spaced transversely extending slots 12 one edge of each of which is sharpened to form a cutter.

Within and upon the bottom of the casing 75 is mounted a bifurcated block 13 having a pivot pin 13' engaged through its arms and on this pin and between the arms are pivotally mounted the lower ends of knives 14 that extend upwardly and divergently 80 through the respective slots 12. Pivoted to the upper end of each of the knives 14 is a link 15 which links in turn are pivoted to the arms 16 that project from the opposite 85 sides of a tubular plunger 17 that is slidably mounted in a guide 18 that is passed through the top and depends within the casing 10. Each of these knives with its link thus forms 90 a toggle and to hold the knives normally and 85 yieldably raised, there is provided a rectangular bar 19, the lower end of which is bifurcated and straddles the block 13, the ends of the bifurcations being pivotally mounted upon the pin 13'. The bar 19 above the 95 block 13, and its bifurcation, lies within the inclosure of the knives and their connected links and the upper end portion of this bar 100 slidably engages the cross-sectionally rectangular tubular plunger 17. Upon the bar 19 is mounted a helical spring 20, that rests with its lower end upon the bed 11 while its upper end bears against the terminal flange 21 at the lower end of the plunger 17.

With this construction it will be noted 100 that when the plunger 17 is depressed, the knives 14 will be swung outwardly and with their upper ends downwardly so that they will progress through the slots 12 with a shearing action against the sharpened edges 105 where the upper face of the bed and one side wall of each of the slots 12, meet.

From the lower portion of the casing 10 there extends forwardly a rest 22, leading 110 from which into the casing, are the guideways 23 that are alined with the corresponding slots 12 so that an envelop laid upon the

rest 22 and moved inwardly through a guide 23, will assume a position projecting for a small portion of one edge, over the corresponding slots 12. If the plunger 17 is then 5 operated, the knives will descend and the projecting portion of the envelop will be cut off and will fall into a drawer 24 in the bottom of the casing.

In order that the envelop may be moved 10 into the casing to the proper degree, a stop block 25 is disposed upon the bed 11 and extends forwardly part way across the slots 12, this block being held yieldably in this position through the medium of a spring 26 that 15 encircles a plunger 27 that extends through the rear of the casing 10 and is carried by the block 25. The side faces of the knives 20 in the direction of the block 25 are beveled as shown at 28 and the central portion of the block 25 is recessed to receive the knives, the 25 ends of the recess being beveled to correspond to the beveled faces of the knives so that they may rest thereagainst. When the envelop is introduced, it stops against the stop block. The knives then descend and their beveled faces urge the stop block rearwardly so as to expose the entire width of the slots 12 to permit the cutoff ends of the envelops to drop readily therethrough and 30 into the drawer beneath. Were it not for the uncovering of the slot, the exposed areas would be so small as to prevent the ready passage of the cutoff ends therethrough.

It will be understood that the drawers may 35 be withdrawn from the casing at any time to discharge their contents.

What is claimed is:—

1. An envelop opener comprising a casing having a bed provided with slots having cutting edges, a knife passed through each slot and pivoted therebelow, a plunger above the bed operatively connected with the knives and having means for holding it normally and yieldably with the knives retracted, a 45 yieldable stop slidably mounted upon the bed and extending part way across the slots in the direction of their cutting edges, the stop being movable from such position under the influence of operative movement of the 50 knives and means for guiding envelops into positions against the stop.

2. An envelop opener comprising a bed

plate having a pair of slots provided with cutting edges, a block disposed below the plate, a pair of knives pivotally connected 55 with the block and extending upwardly and through the corresponding slots, a plunger having link connections with the opposite ends of the knives for movement thereof in co-operative relation to the cutting edges of 60 the slots when the plunger is actuated, a rod having one end bifurcated and mounted upon the pivot of the knives in position to embrace them and the blocks, the opposite end of the rod slidably engaging the plunger, and a return spring for the plunger disposed upon the rod and bearing with its ends against the plate and plunger, respectively.

3. An envelop opener comprising a plate 70 having a cutting edge, a knife pivoted below the plate and extending above the plate in co-operative relation to the cutting edge and having means for actuating it in shearing relation to the cutting edge, and an envelop 75 stop plate yieldably held in definite spaced relation to the cutting edge and having a bevel, the blade having also a bevel arranged to engage the bevel of the stop plate in its shearing movement and under the influence 80 of which engagement the stop plate is movable away from the cutting edge.

4. An envelop opener comprising a base having a pair of cutting edges, an envelop 85 stop plate slidably mounted upon the base and held yieldably with spaced portions thereof in spaced relation to the cutting edges respectively, said spaced portions having bevels, cutting blades pivoted below the base and extending from above in co-operative 90 relation to the cutting edges and having bevels disposed to engage respectively the first named bevels when the blades are moved in shearing relation to the cutting edges and under the influence of which the stop plate is 95 movable away from the cutting edges, and means connected with the blades for operating them simultaneously.

In testimony whereof, I affix my signature, in the presence of two witnesses.

JOHN A. MULLIGAN.
